UNITED STATES PATENT OFFICE.

WILLIAM A. LIVERPOOL, OF MULLICA HILL, NEW JERSEY.

DESIGN FOR A GARDEN-TOOL.

SPECIFICATION forming part of Design No. 31,039, dated June 20, 1899.

Application filed May 22, 1899. Serial No. 717,850. Term of patent 7 years.

To all whom it may concern:

Be it known that I, WILLIAM A. LIVERPOOL, a citizen of the United States, residing at Mullica Hill, in the county of Gloucester and State 5 of New Jersey, have invented and produced a new and useful Design for a Garden-Tool, of which the following is a specification.

In the accompanying drawing, forming part of this specification, I have shown a perspective view of a garden-tool constructed in accordance with my design, the essential feature of my design consisting in the peculiar construction of the blade and also in the prong attached to the said blade.

15 Referring especially to the drawing, A represents the blade, having the rounded edges A' and the central curved depression A², the handle B being connected to the blade in the usual manner. Prongs C extend upwardly

from the upper edges of the blade, said prongs being curved, as shown at C', and pointed, as shown at C². Longitudinal openings C³ are shown upon the lower portion of the prongs C.

D represents the heads of bolts or rivets.

A garden-tool constructed in accordance 25 with this design can be used either as a hoe or it can be used as a hand-cultivator, the prongs serving as teeth or digs.

Having thus fully described my invention, what I claim as new, and desire to secure by 30 Letters Patent, is—

The design for a garden-tool, substantially as herein shown and described.

WILLIAM A. LIVERPOOL.
